Patented Feb. 22, 1921.

William A. Snyder INVENTOR

UNITED STATES PATENT OFFICE.

WILLIAM A. SNYDER, OF LOS ANGELES, CALIFORNIA, ASSIGNOR OF ONE-HALF TO
EARL P. RUNDLE AND ANNA RUNDLE, BOTH OF LOS ANGELES, CALIFORNIA.

TABLE.

1,369,199.

Specification of Letters Patent. Patented Feb. 22, 1921.

Application filed April 26, 1920. Serial No. 376,586.

To all whom it may concern:

Be it known that I, WILLIAM A. SNYDER, a citizen of the United States, residing at Los Angeles, in the county of Los Angeles 5 and State of California, have invented a new and useful Table, of which the following is a specification.

This invention relates to devices in the form of tables to be folded so as to take up 10 little room when in folded condition.

One of the objects of this invention is to provide a proportionally large table top.

Another object is to make it possible that the top can be set horizontal while the legs 15 are set on a ground not horizontal.

Another object is to make it possible that the top can be set inclined as in a writing desk retaining its stable form.

Another object is to provide a table top 20 swingably engaging in approximately halves having legs, engaging near this point, normally projecting downwardly in the direction of both ends of the complete table.

Another object is to provide legs of a 25 table with a swinging joint at their top ends swingably engaging with the table top at about the middle to the underside of the table top so that the lower ends of the legs project downwardly in the direction of the 30 two ends of the table.

Another object is to provide legs, table tops, and bracing and connecting member for a table of such a form that the whole 35 table can easily be folded to the possibly smallest bundle or package.

Other objects will appear from the following description and appended claim as well as from the accompanying drawing, in which—

40 Figure 1 is a perspective view of the whole device.

Fig. 2 is a fragmentary detail side elevation of a slightly modified form of interconnecting the several members of the 45 device.

The table tops 3 and 4 normally constitute in their combined form a complete table top. The two members 3 and 4 are therefore preferably interconnected by some kind 50 of hinges or similar suitable devices 5 which allow the tops to swing one in relation to the other, and preferably by such devices which will allow a folding of the tops in such a manner that the top surfaces come 55 one against the other in folded position

while the tops can also be moved so that the center of the table can be raised while the ends 6 and 7 are a suitable distance lower than the center portion 8. The legs 9 and 10 are preferably made in form of a 60 frame to operate as one member, and the legs 11 and 12 are also made in form of such a frame to operate as another single member. Such frames are arranged one opposite to the other and interconnected by 65 hinges or similar devices 13 which allow a swinging of the frames toward each other. One of the frames is then swingably engaged to one of the top members 3 or 4, in the drawing the frame formed by the legs 70 9 and 10 is swingably engaged to the top member 3 by the hinges 14.

Under this arrangement, the top member 4 folds over to rest on the top member 3, the legs 9 and 10 fold so as to come to rest 75 against the underside of the top member 3, and the legs 11 and 12 fold so as to come to rest against the legs 9 and 10.

Of course, the frame formed by the legs 9 and 10 can be made smaller to fit within 80 the frame formed by the legs 11 and 12 when in folded position, as will easily be understood, or the last-named frame can be smaller than the first-named frame, as long as one frame fits within the other, to take 85 up the smallest space possible with such a device, and such minor modifications can be made without departing from the spirit of this invention. In Fig. 2, the upper end 15 of the leg 16 is shown to be outside of the 90 upper end 17 of the leg 18, to make up such or a similar modified form as just referred to in the above. The top member 19 is engaged in this modified form to the leg 16 by the hinge 20, while the top member 21 95 is engaged to the leg 18 by the hinge 22.

Braces 23, also preferably made in form of a frame, and preferably pivotally engaged at 24 with the legs 9 and 10, serve to support the end 7 of the table top 3 in 100 normal position. The engaging block or member 25 is preferably provided on the table top 3 to prevent a slipping of the braces and to properly support the top so in normal position. The braces 27 engage 105 pivotally at 28 with the legs 11 and 12 to normally serve as a support for the end 6 of the table top 4. The engaging block or member 29 serves to prevent a slipping of the braces and to properly engage and sup- 110

port the top 4. A connecting rod 30 is provided on each side of the table to connect the legs 9 and 11 on one side of the table, and the legs 10 and 12 on the other side of 5 the table, preferably swingably engaged at one end as at 31 and removably engaged at the other end of the rod, as at 32. A cable or cord, or any other flexible member 33 is preferably provided on the cross bars as at 10 34 to prevent the legs from spreading too far apart.

The whole device can be folded together in the manner described and indicated above. The table tops 3 and 4 are prefer- 15 ably of the length of the legs.

A table is naturally of a normal height to be comfortable, and, to make this table of such normal height, the legs 9, 10, 11 and 12 must naturally be longer than if vertical 20 or nearly vertical. Spreading the legs apart in the manner as illustrated in the drawing allows naturally a corresponding length to the table tops as long as the table tops must fold toward the legs, and this provides for 25 a proportionally long table when considering the double length obtained by the double spread of the oppositely arranged legs, as will easily be understood from the illustration.

30 Making the several parts to fold one within the other or practically so, when considering the thickness of one member applied to the other makes it naturally clear that the whole device need not to be very 35 much thicker than the two table tops in addition to the thickness of one leg, since all other legs and braces and other members are made to fold within the space of the thickness of the one leg.

40 The several parts of this device can naturally be made out of wood or any other suitable material, sheet metal and steel bars would naturally allow a considerable reduction in the thickness of the device when in 45 folded condition, as will easily be understood.

Spreading the legs in the manner as illustrated in the drawing naturally requires means for preventing the legs from spreading out too far, the members 30 and 33 50 being intended for this purpose but, of

course, slightly modified forms can easily be substituted without departing from the spirit of the invention.

Lifting the center portion of the table at 55 8 naturally brings the legs closer together and the legs can be set so by providing notches or other similar provisions 35 in the members 30. Both table tops 3 and 4 then naturally come into a sloping position, the 60 center forming the upper or higher edge of both table tops 3 and 4 while the ends 6 and 7 respectively form the lower edges of the corresponding tops. Such a setting of the table allows its use as writing tables with 65 inclined tops at opposite sides, as will easily be understood.

Having thus described my invention, I claim:

In a table of the class described, a table 70 top consisting of halves having means for swingably engaging the halves along the adjacent edges, one pair of legs having means for swingably engaging with one of the halves of the top at a point near the 75 engaging edges of the halves of the top, another pair of legs having means for swingably engaging with the first-named legs near the engaging edges of the top but in no direct engagement with the top, both 80 pairs of legs normally projecting downwardly and toward the ends of the top for supporting the top adapted to be folded alongside of the underside of one of the halves of the top while the top is folded 85 with the top surfaces of the halves coming together, bracing members disposed between the legs and the top near the ends of the legs and the tops, and means for setting the legs and the top in suitable relation to one 90 another for forming a table, all legs and braces being located on the underside of one of the halves of the top while the halves are folded with the top surfaces coming together when the device is in folded position. 95

In testimony that I claim the foregoing as my invention I have signed my name in the presence of two subscribing witnesses.

WILLIAM A. SNYDER.
